UNITED STATES PATENT OFFICE.

LAVERN BORDWELL, OF NEW YORK, N. Y.

BEATER.

Application filed February 20, 1928. Serial No. 255,794.

This invention relates to improvements in beaters or mixers of that type adapted to be manually operated for effectively beating or mixing one or more materials contained 5 in a receptacle.

The primary object of the present invention is to provide a beater which is extremely simple and durable in construction and which embodies parts which may be economically manufactured and readily assembled to insure the production of a uniformly desirable and efficient product or beater.

A further object is to provide an improved connection between the legs of the supporting loop for the beater blades and the legs of the handle carrying supporting frame for the driving gear.

A still further object is to provide improved means for effectively preventing separation or spreading of the legs of the loop and frame so that maintenance of the driving pinions for the beater blades in mesh with the driving gear is most positively insured, 25 such means also effectively preventing movement of the legs toward each other so that binding of the rotatable parts is most effectively prevented.

Another object is to provide for the operative positioning of the spur pinions in overlapping planes, whereby riding of one pinion upon the other is prevented and effective engagement of both pinions with a flat driving gear is attained and insured.

Still another object is to provide a beater composed of parts so designed and connected as to entirely avoid the use of separate securing elements such as screws, rivets and the like.

Other objects will appear as the nature of the invention is better understood, and the same consists in the novel form, combination and arrangement of parts herein-after more fully described, shown in the 45 accompanying drawing and claimed.

In the drawing:—

Figure 1 is an elevational view of a beater embodying the present invention;

Figure 2 is a fragmentary side elevational 50 view showing the portion of the beater adjacent the driving gear and spur pinion, as seen looking toward the right of Figure 1;

Figure 3 is an enlarged horizontal section on line 3—3 of Figure 1;

Figure 4 is a perspective view of the pinion guard and leg bracing elements; and

Figure 5 is a fragmentary perspective view, partly broken away, of the driving gear supporting frame.

Referring more in detail to the drawing, the present type of beater embodies two adjacently disposed pairs of beater blades 5 and 6 having outwardly curved lower operative end portions and rotatably mounted at their upper and lower ends on the legs 7 of a U-shaped supporting loop 8, a spur pinion 9 being fixed upon the upper end of each pair of beater blades in a substantially horizontal position and adapted to mesh with a vertically disposed driving gear 70 mounted between the spaced legs 11 of a frame carrying a handle 12 at the upper end thereof and having the lower ends of its legs 11 connected to the upper ends of the legs 7 of the loop 8. The driving gear 10 is carried by a suitable horizontal shaft 13 mounted in the legs 11 and equipped with a suitable operating handle 14 at one end.

In accordance with the present invention, the upper ends of the beater blades 6 are disposed slightly higher than those of the blades 5 so that the spur pinions 9 are disposed in different horizontal planes and overlapped at their inner sides in slightly spaced relation for simultaneous engagement with the driving gear 10, which is of the flat type or provided with a single set or circular series of teeth. By reason of this construction, a most simple and inexpensive form of driving gear can be employed, and effective driving engagement of the pinions 9 with the gear 10 is insured without liability of the pinions riding one upon another so as to cause binding or unevenness of action.

The present invention also embodies the provision of improved means for rigidly connecting the adjacent ends of the legs 7 and 11 and for effectively bracing them against separation or movement toward each other such as might cause binding of the gearing parts or destruction of effective driving connection therebetween. For this purpose the lower ends of the legs 11 have the side portions thereof directed laterally in the form of outwardly projecting normally parallel flanges 15 to form sockets open at the outer sides to permit lateral introduction of the upper ends of the legs 7 into the same, the upper ends of the legs 7 having inturned extensions 16 adapted to be entered into and fitted in suitable open-

ings 17 provided in the legs 11 above the flanges 15, when the legs 7 are so introduced between the flanges 15 or the sockets formed partially thereby. A pinion guard and leg bracing element is provided including an elongated plate 18 having downwardly diverging side wings or tongues 19 intermediate the ends thereof and provided with a central transverse slot 19^a which extends into the wings 19 to provide clearance for the driving gear 10 where it meshes with the pinions 9. The plate 18 also has tongues 20 stuck upwardly and outwardly therefrom at opposite sides of the slot 19^a centrally of the plate 18, so as to form a further slot 21 intersecting and disposed at right angles to the slot 19^a, the tongues 20 projecting upwardly from the plate 18 at the ends of the slot 21. The upper end portions of the legs 7 of the loop 8 are passed upwardly through the slots 21 and disposed against the inner sides of the tongues 20, the latter being positioned in the sockets formed by the flanges 15, and the plate 18 being disposed to abut the lower ends of the flanges 15. The free vertical edges of the flanges 15 are then bent together and clinched about the tongues 20 and the adjacent portions of the legs 7 as indicated at 22, thereby firmly and rigidly connecting the parts without the use of separate fastening means. In this way, the supporting loop 8 for the beater blade and the handle carrying supporting frame for the driving gear 10 are most durably and rigidly connected, and the pinion guard and bracing element is also firmly secured in place so that absolutely no freedom of movement is allowed between the respective legs of the loop 8 and the frame and consequently binding or disengagement of the gearing parts is effectively prevented. The engagement of the extensions 16 in the openings 17 effectively prevent relative longitudinal displacement of the loop 8 and the driving gear supporting frame, thereby holding the pinions 9 against the underside of the plate 18 and firmly binding it against the lower ends of the sockets partially formed by the flanges 15. Obviously, this avoids any play whatever of the tongues 20 in the closed sockets formed by inturning the free edges of the flanges 15. Moreover, the opposite end portions of the plate 18 are offset in different horizontal planes to overlie and substantially cover the pinions 9 so as to act as guards therefor which are effectively braced and connected by portions of the tongues 19 at both sides of the plate 18. The openings 23 in the legs 11 are those in which the shaft 13 of the driving gear 10 is journaled.

It will be noted that the supporting frame for the driving gear consists of two similar strips of strap metal having contiguous upper end portions 24 riveted or welded to

gether and terminating in their upper ends in tangs suitably fastened in the handle 12. In other words, the handle 12 is suitably fastened on the tangs provided on the upper ends of the strip members whose lower end portions are of slightly different lengths and spread apart in spaced parallel relation to form the legs 11 of different lengths as shown clearly in Figure 1.

It is obvious from the foregoing that the various parts can be readily stamped and assembled so as to insure uniform quantity production in which each beater or article is extremely light in weight, unusually durable in construction and effective in operation.

Minor changes may be made without departing from the spirit and scope of the invention as claimed.

What I claim as new is:—

1. In a beater, a handle carrying frame having spaced legs formed with openings near their lower ends, a beater blade supporting loop having legs with their upper end portions disposed against the lower end portions of said legs of the frame, said legs of the supporting loop having lateral extensions on the upper ends fitted in the openings of the frame legs, and laterally projecting flanges on the side edges of the lower end portions of the frame legs moved into snugly embracing engagement with the upper end portions of said legs of the supporting loop.

2. In a beater, a handle carrying frame having spaced legs formed with openings near their lower ends, a beater blade supporting loop having legs with their upper end portions disposed against the lower end portions of said legs of the frame, said legs of the supporting loop having lateral extensions on their upper ends fitted in the openings of the frame legs, laterally projecting flanges on the side edges of the lower end portions of the frame legs adapted to be moved into snugly embracing engagement with the upper end portions of said legs of the supporting loop, and a bracing element disposed on the legs of the supporting loop against the lower ends of the frame legs and having upstanding tongues tightly embraced by said flanges.

3. In a beater, a handle carrying frame having spaced legs formed with openings near their lower ends, a beater blade supporting loop having legs with their upper end portions disposed against the lower end portions of said legs of the frame, said legs of the supporting loop having lateral extensions on their upper ends fitted in the openings of the frame legs, laterally projecting flanges on the lower end portions of the frame legs snugly embracing the upper end portions of said legs of the supporting loop, a bracing element disposed on the legs of the supporting loop against the lower

ends of the frame legs and having upstanding tongues tightly embraced by said flanges, said tongues of the bracing element being disposed against the sides of the legs of said supporting loop.

4. In a beater, a handle carrying frame having spaced legs formed with openings near their lower ends, a beater blade supporting loop having legs with their upper end portions disposed against the lower end portions of said legs of the frame, a beater blade rotatable on each leg of the loop, said legs of the supporting loop having lateral extensions on their upper ends fitted in the openings of the frame legs, laterally projecting flanges on the lower end portions of the frame legs snugly embracing the upper end portions of said legs of the supporting loop, one of said beater blades being shorter than the other, a bracing element embodying a plate formed with a transverse slot and having an end portion at one side of said slot offset upwardly against the shorter beater blade, spur pinions fixed on the upper ends of the beater blades and disposed in different planes against the underside of the bracing plate at opposite ends of the latter, and a single driving gear journaled in the frame and projecting through the slot of the bracing plate into constant mesh with both pinions.

5. In a beater, a handle-carrying frame having spaced legs, a loop having legs for supporting beater blades of different lengths and connected at their upper ends to the lower ends of the frame legs, spur pinions fixed on the upper ends of the beater blades and disposed in different planes, a single driving gear journaled in said frame and constantly meshing with said pinions, and a combined bracing and pinion guard plate mounted on the legs of the supporting loop, and said bracing plate having an offset portion compensating for the beater blade of

different length and the disposition of the spur pinions in different planes.

6. In a beater, a handle carrying frame having spaced legs, a beater blade supporting loop having legs interlocked with the legs of said frame, a bracing plate on the legs of the loop above the beater blades and having upstanding members, and means on the legs of the frame tightly embracing the legs of the loop and the upstanding members of the bracing plate to securely connect the frame and loop and secure the bracing plate thereto to resist relative spreading or inward movement of the legs of the loop and frame.

7. In a beater, a beater blade supporting loop and a driving gear supporting frame, each having legs with interlocking ends and a brace plate interengaged with the interlocked ends of the legs to prevent lateral spreading thereof.

8. In a beater, a beater blade supporting loop and a driving gear supporting frame, each having legs with interlocking ends and a brace plate interengaged with the interlocked ends of the legs to prevent lateral spreading thereof, the leg connection including flanges on one set of legs looped around the ends of the other set of legs and means on the plate confined by the leg flanges for rigidly mounting the plate.

9. In a beater, a beater blade supporting loop and a driving gear supporting frame, each having legs with interlocking ends and a brace plate interengaged with the interlocked ends of the legs to prevent lateral spreading thereof, the leg connection including flanges on one set of legs looped around the ends of the other set of legs and fingers struck out from the plate and confined by the loop formed by the leg flanges for rigidly mounting the plate.

In testimony whereof I affix my signature.

LAVERN BORDWELL.
